DESIGN FOR AN OIL BURNER

Adolph Thousand, Cedar Rapids, Iowa

Application September 21, 1935, Serial No. 58,651

Term of patent 7 years

To all whom it may concern:

Be it known that I, Adolph Thousand, a citizen of the United States, residing at Cedar Rapids, in the county of Linn and State of Iowa, have invented a new, original, and ornamental Design for an Oil Burner, of which the following is a specification, reference being had to the accompanying drawing, forming part thereof.

I claim:

The ornamental design for an oil burner as shown.

In witness whereof, I hereunto subscribe my name this 19th day of September, 1935.

ADOLPH THOUSAND.
